FISHING LURE

Lawrence E. Morrissette, 340 Bd des Ecoles,
83140 Six Fours Plages, France

Filed Aug. 20, 1973, Ser. No. 389,489

Term of patent 14 years

Int. Cl. D22—05

U.S. Cl. D22—29

FIG. 1

FIG. 2

FIG. 3

FIG. 4

FIG. 1 is a side elevational view of a fishing lure embodying my invention;

FIG. 2 is a side elevational view of the same taken at approximately ninety degrees (90°) rotation about its longitudinal axis from the position from which FIG. 1 is taken;

FIG. 3 is a front end elevational view of the same; and

FIG. 4 is a rear end elevational view of the same.

I claim:

The ornamental design for a fishing lure, as shown and described.
